CLAIM

The ornamental design of a ceiling hanging curved LED light fixture, as shown and described.

DESCRIPTION

FIG. 1 is a perspective view of a design of a ceiling hanging curved LED light fixture as viewed looking up;

FIG. 2 is a right end view of the light fixture of FIG. 1, with the left end view being identical;

FIG. 3 is a front view of the light fixture of FIG. 1, with the rear view being identical; and,

FIG. 4 is a bottom view of the light fixture of FIG. 1, as viewed looking straight up.

The top surface of the ceiling hanging curved LED fixture is not visible in use when hung from a ceiling and forms no part of the claimed design. The dashed lines show unclaimed environment.
